QUICK-CHANGE CHUCK

Kurt Hässner, Gera, Germany

Application December 8, 1931, Serial No. 579,777,
and in Germany October 18, 1930

4 Claims. (Cl. 279—76)

The present invention relates to a quick change chuck for machine tools, particularly drills, with an inserted element for holding the tool, which can be so fixed by a locking device that the 5 tool cannot displace itself longitudinally within the chuck. The principal object of the invention is to provide means whereby the inserted element can be easily and quickly inserted into or dismounted from the chuck, both when the machine 10 is stopped and while it is working. According to the present invention this object is mainly ensured by the fact that the locking device consists of locking levers surrounded by a ring which is arranged on the chuck so that it can slide 15 longitudinally, the ring having surfaces which co-act with the locking levers in such a way that by sliding the ring the locking levers are caused to lock with, or disengage from, the inserted element. The ring consists preferably of two ring 20 sections which can be placed on to the chuck from both sides, and are connected by screws or some similar means. In order to ensure that when the inserted collar is pushed into the chuck the levers will engage automatically, a spring is 25 suitably arranged which normally holds the ring in the position in which the locking levers are in the locking position.

The transmission of the rotating movement from the chuck to the inserted element (which 30 is of collar form) is suitably ensured by a lug arranged on the upper end of the inserted collar, which engages with a transverse groove of the chuck and is provided with a half-cylindrical rounded part, so that the insertion of the inserted 35 collar into the chuck while the machine is working is an easy matter.

The drawings show by way of example one embodiment of the invention.

In these drawings:—

40 Fig. 1 is a longitudinal section through the quick change chuck with the inserted collar and with the locking levers in locking position,

Fig. 2 is a similar section in the unlocked position of the locking levers.

45 Fig. 3 is a sectional view of an alternative form of construction in which the collar is inserted directly into a suitably shaped lower end of a rotating spindle.

Fig. 4 is an axial section through another 50 modification,

Fig. 5 is a section similar to Fig. 4, this section being taken at 90° with respect to Fig. 4 on line 5—5 of Fig. 4,

Fig. 6 is also a view similar to Fig. 4, showing 55 still another modification; and

Fig. 7 is a longitudinal section through Fig. 6, on the line 7—7 thereof.

In the construction shown in Figs. 1 and 2 the chuck consists of a mainly cylindrical case or casing F which at its upper end is provided with 60 a cone-shaped journal F¹. In the case F are in longitudinal direction a number of slots or cut out parts, in which are arranged a corresponding number of locking levers B. The locking levers B are surrounded by an axially slideable 65 ring, which consists of two ring sections R¹ and R² which slide on to the case F and are firmly connected one with the other by threads or some other suitable means. Between the lower end of the ring section R² and a shoulder provided on 70 the case F is arranged a spring D which tends to press downward the ring R¹, R² consisting of two sections which is slidably arranged on the case F.

In the bore of the case F is inserted a collar E 75 which at its upper end is provided with a half cylindrically rounded lug M, which engages with a transverse groove of the case F. The bore E¹ in the inserted collar is cone-shaped in the known manner and serves for the purpose of inserting 80 the shaft of a drill or other tool. On the outer circumference of the inserted collar E is a groove or conical surface G, the wall or shoulder G' of which, facing the upper end of the inserted collar, is comparatively steeply inclined, while the 85 other wall G² runs over comparatively flatly into the outer circumference of the case E.

The locking levers B which are enclosed in the two-part ring R¹, R² are at their upper and lower 90 ends narrower than in the intermediate part and have at the outer side of the lower part a bevelled part B¹. The upper and lower ends of the locking levers B co-act with the inclined or cam surfaces C¹, C² respectively, which are on the inner 95 side of the ring sections R¹, R², the said inclined surfaces being so arranged that when the ring R¹, R² is moved upwards, by overcoming the tension of the spring D, the locking levers B are so pivoted by the inclined surface C² which engages with their lower ends, that their upper ends 100 moved outwardly, while with the subsequent downward movement of the ring R¹, R² the locking levers B are again moved inwardly by the inclined surface C¹ which engages with their upper ends.

In the position of the parts illustrated in Fig. 1, the two-part ring R¹, R² is in its lower position, so that the locking levers B are pivoted with their upper ends towards the inner side, and engage 105 with the conical surface G which is on the outer 110

circumference of the inserted collar E. This ensures that the inserted collar E is prevented by the locking levers B from being pulled out from the chuck F. If the inserted collar E is to be pulled out from the chuck, all that is necessary is to push the ring R¹, R² upwardly against the tension of the spring D. This displacement causes the locking levers B, through the action of the inclined surface C², to move from the locking position shown in Fig. 1 into the position shown in Fig. 2, in which the upper ends of the levers are disengaged from the conical surface G of the inserted collar E, so that the collar E can be pulled out in a downward direction. When the ring R¹, R² is released again, it moves downwardly again under the action of the spring D, so that the locking levers B move back into the position shown in Fig. 1.

When the collar E is inserted into the chuck F, the locking levers B are moved outwardly by the part of the collar E which is above the conical surface G, while at the same time the ring R¹, R² slides upwardly. As soon as the collar E has been entirely inserted, so that the lug M is entirely in mesh with the transverse groove of the chuck F, the ring R¹, R², by the action of the spring D moves downwardly and the locking levers B by the action of the inclined face C¹ are engaged with the groove G of the inserted collar E.

The insertion or removal of the collar E can be carried out when the machine is stopped and also while the drill or other machine tool is working, and this ensures an exceedingly quick and easy change of the tool. The working of the device is quite independent from the position of the chuck, so that the chuck can be used in an inclined or horizontal position instead of in the vertical position.

The construction shown in Fig. 3 differs from the one shown in Figs. 1 and 2 principally in that the chuck F is formed direct by the correspondingly shaped lower end of the spindle S of a drill or other tool machine. This arrangement has the advantage that the tools will lie very close to the bearing L of the spindle S.

In the constructional forms shown in Figs. 4-7 the collar E is rotated by the case F by the intermediary of a catch member which is exchangeably attached to said case and is provided with a transverse groove engaged by the lug M of said collar. In Figs. 4 and 5, N¹ denotes said catch body, which is cylindrical at its exterior circumference which engages a correspondingly shaped bore of the case F and is provided at its upper side with a threaded stud O screwed into a correspondingly threaded bore of the case F.

In the further modification shown in Figs. 6 and 7 N² is the catch body which in this case has no threaded stud, but is threaded at its exterior circumference. A corresponding thread is provided in the case F. Owing thereto, the catch body N² can be easily exchanged, which is true

also of the catch-body N¹ (Figs. 4 and 5). The collar E can be very reliably centered, as well as guided, in the case F.

I claim:

1. A quick-change chuck for machine tools, particularly drills, comprising a casing; a tool-holding member adapted to be inserted in said casing and having a shoulder; independent means for transmitting rotation from the casing to the tool holding member; a ring provided around said casing and the tool-holding member and having an inner cam surface at each end thereof; and a straight locking member arranged within the ring and being loosely and tiltably mounted to tilt against and secure the tool-holding member in the casing, said ring being adapted to slide axially with a relatively short movement to tilt the locking member into and out of engagement with the tool-holding member when the respective end of the locking member contacts with its cooperating cam surface of the ring, and said locking member when in engagement with the tool-holding member being in a position to abut at one end against the shoulder and at the other end against the ring. 95

2. A chuck according to claim 1, in which a spring is provided around the casing and bearing against the ring to normally maintain the ring so that the tool-holding member will be in 105 locked position in the chuck.

3. A quick-change chuck for machine tools, particularly drills, comprising a casing; a tool-holding member adapted to be inserted in said casing and having a groove therein; independent 110 means for the transmitting rotation from the casing to the tool-holding member; a ring, provided around said casing and having an inner cam surface at each end thereof; and a plurality of straight locking members arranged within the 115 ring being in the form of tiltable levers which are loosely mounted to tilt against and secure the tool-holding member in the casing, said ring being adapted to slide axially on the casing with a relatively short movement to tilt the locking 120 members into or out of engagement with the grooves of the tool-holding member when the respective ends of the holding members contact with their cooperating cam surface of the ring, and said locking members when in engagement 125 with the tool-holding members being in a position to abut at one end in the groove and at the other end against the ring.

4. A chuck according to claim 3, in which a spring is provided around the casing and bearing 130 against the ring to normally maintain the ring in position so that the tool-holding members will be in engagement with the groove of the tool-holding member.
